INVENTOR:
ALEXANDER E. BLOCK.
By *James L. Hopkins*,
ATTORNEY.

UNITED STATES PATENT OFFICE.

ALEXANDER E. BLOCK, OF ST. LOUIS, MISSOURI.

SHOE AND METHOD OF MAKING SAME.

Application filed February 4, 1926. Serial No. 85 857

My invention relates to improvements in shoes and methods of making shoes, and has for its object the novel use and method of disposing of the bottom edges of the upper materials to eliminate cupping in the finished shoes beneath the heel of the wearer, and to provide a substantially flat heel-receiving portion in the bottom of the finished shoe.

5 edges may be curved or irregular, and may be transverse or oblique with reference to the length of the shoe, all as may be desired by the manufacturer with regard to economy of the upper materials.

40 By the term "upper materials" as employed herein, I refer to such layers of material as embrace the counter above the level of the shoe-heel, and are customarily so trimmed as not to fill the heel-area C, but so as to leave 45 an unfilled space within that heel-area C which must be filled with some reinforcing material to prevent the cupping of the heel-receiving area of the shoe.

45 The heel-area filling materials 4 are secured in place to form a substantially flat surface above the heel B by means of nails 5 or other suitable fastening means.

10 Drawings.

In the drawings—

Fig. 1 is a bottom view of the rear portion of a shoe embodying, and produced by the 15 method of my invention, before the shoe is heeled.

Fig. 2 is a transverse vertical view of the same in section, the heel being in place, taken on the line 2—2 of Fig. 1.

20 Description.

In the illustrated shoe A the welt 3—3 terminates at a point slightly in advance of the breast of the heel B.

25 The upper materials 4 are cut of a length sufficient to fill the flat space or area C (as shown in Fig. 1) upon which the heel B is to be mounted (as shown in Fig. 2).

While I have illustrated the upper materials 4 as cut to meet at a median line in the area C, it is not necessary that they be so cut, as their line of meeting need not be centrally located and need not be straight. My invention is present wherever the upper materials 35 are cut to fill the area C, and their meeting

Claims.

I claim:—

1. The improved method of shoe manufacture comprising the cutting of the lower margins of the upper materials to a length sufficient to fill the heel area of the shoe; securing said lower margins to form a substantially flat surface; and mounting a flat-topped heel on said flat surface.

2. The shoe comprising a flat heel surface formed of the lower meeting margins of the upper materials and a flat-topped heel mounted beneath said surface.

In testimony whereof I hereunto affix my signature.

ALEXANDER E. BLOCK.
